UNITED STATES PATENT OFFICE.

DONALD BARNS MORISON, OF HARTLEPOOL, ENGLAND.

APPARATUS RELATING TO THE WITHDRAWAL OF AIR AND WATER FROM STEAM-CONDENSERS.

1,130,319.

Specification of Letters Patent.

Patented Mar. 2, 1915.

Application filed April 18, 1914. Serial No. 832,957.

To all whom it may concern:

Be it known that I, DONALD BARNS MORISON, a subject of the King of Great Britain and Ireland, residing at Hartlepool, in the county of Durham, England, have invented Improvements in Apparatus Relating to the Withdrawal of Air and Water from Steam-Condensers, of which the following is a specification.

10 This invention relates to improvements in steam condensing apparatus working under vacuum wherein air is withdrawn from a condenser by a steam jet and is thereafter discharged as by an air pump of any type. 15 In apparatus of this kind, it is known practice to place an auxiliary surface condenser between the steam jet and a reciprocating air pump, the condensing water to the auxiliary surface condenser being supplied from 20 the same source as the condensing water for the main condenser, as for example from the sea. In such an arrangement the heat in the steam from the steam jet which is absorbed by the condensing water is lost. 25 The object of the present invention is to enable an air pump of given volumetric capacity to discharge more air than heretofore by means of apparatus wherein the steam from a steam jet which discharges the 30 aerated vapor from the condenser is condensed in a heater by water suitable for use in a boiler as for example by the condensate from a condenser; the temperature of the condensing water for use in the heater being 35 controlled by being cooled, when required, in the condenser, for the purpose of varying the air withdrawing capacity of the air pump in accordance with the amount of air to be withdrawn, with a minimum thermal 40 loss.

In the accompanying drawings, Figure 1 is a diagrammatic elevation of one embodiment of the invention; Fig. 2 is a similar view of a modified form of the apparatus; 45 Fig. 3 is a side view of a part of a modified form of the apparatus, a portion thereof being in section; Fig. 4 is a side view partly in section of a modification of the form shown in Fig. 2; Fig. 5 is a side view partly 50 in section showing a further modification of Fig. 2; Fig. 6 is an elevation partly in section of another form of the apparatus; Fig. 7 is an elevation partly in section of a modification of Fig. 2.

In Fig. 1 the aerated vapor is discharged from a condenser *a* by a steam jet device *b* into a heater *c* of the direct contact type. Condensate is withdrawn from the condenser through the pipe *y* by the reciprocating pump *g* provided with a tank *r* into 60 which the condensate preferentially flows and from which a quantity is delivered through the valve *e* and the pipe *f* into the heater *c*.

With the object of providing cool condensing water for the heater at times when the condensate formed in the condenser is reduced or ceases, a float controlled valve *v* is provided in the tank *r* so that water is admitted by the valve *v* through the pipe *t* 70 into the condenser and is reduced in temperature whenever the condensate formed in the condenser is insufficient to condense the steam from the steam jet, the cooled water being withdrawn from the condenser 75 by the pump *g* and delivered from the tank *r* to the heater *c*, thus automatically regulating the delivery of water to the heater and controlling its temperature by cooling it in the condenser. Under normal conditions, 80 that is, under full load, the valve *v* does not operate, as there is always more water discharged from the condenser than is required for condensing purposes in the heater *c*. But when condensation ceases, the water 85 in the tank *r*, is in continuous circulation through the heater *c*, and consequently increases in temperature. Therefore, when the water in tank *r*, falls below a certain level, the float opens the valve *v*, and water 90 is passed into the condenser and withdrawn from it in a cooled state and suitable for use in the heater *c*, for condensing purposes, thus always maintaining a quantity 95 of cool water when no steam is being condensed in the condenser. The aerated vapor discharged from the condenser into the heater *c* is withdrawn from the heater together with the heated water through the pipe *l* by the air pump *h* which also has its 100 suction system connected by the valve *o* with the pump *g* and the condenser *a*, so that in the event of either pump becoming deranged, the other pump may be employed for withdrawing aerated vapor and condensate from the condenser, or both pumps 105 may be employed for withdrawing aerated vapor and condensate from the condenser,

without the aid of the steam jet device, in the manner described in the specification of Letters Patent No. 1006975 of 1911.

In Fig. 2, the condensate is discharged 5 from the condenser by a rotary pump g , and is delivered in part or wholly through the valve e and pipe f into the heater c from which aerated vapor is withdrawn by the pump h that is supplied with cooled water 10 by way of the valve j and pipe k from the cooler x in a known manner. The heated condensate is delivered from the heater c through a water sealed looped pipe w into a vertical pipe u connected with the upper 15 and lower portions of the condenser, a valve i being inserted in the pipe. Under normal conditions when the condenser is under full load, a portion of the condensate is delivered through the pipe f into the heater c wherein 20 it is heated and from whence it flows through the pipes w and u into the lower portion of the condenser where it mixes with the condensate which is thereby beneficially raised in temperature. When the 25 condensate produced in the condenser is reduced to such an extent that the water circulating through the heater becomes too hot to condense the steam therein, then the valve i is partly or wholly closed so that water 30 from the heater is delivered into the upper portion of the condenser over the cooling surface, whereby a reduction in the temperature of the water is effected.

In Fig. 3 the whole of the condensate is 35 withdrawn from the condenser by the pump g and is delivered into the heater c from which it is discharged by the pump g , the arrangement being similar to that described and illustrated in the specification of Letters Patent No. 967810 of 1910. The aerated vapor is withdrawn from the heater c by a dry air pump h which may be of the slide valve air admission type. The valve v controls the quantity of water delivered by the 45 pump g into the condenser from which it is discharged by the pump g to the heater c , the valve v being operated by a diaphragm in the device 6 that is controlled by the absolute pressure in the heater c . The arrangement is such that when the condensate delivered from the condenser is insufficient to condense the steam in the heater c , the pressure in the heater by rising causes the diaphragm in the device 6 to open the valve 50 v and thus admit water from the discharge of the pump g into the condenser, whereby the temperature of the condensing water delivered to the heater can be controlled.

Fig. 4 is a modification of Fig. 2, and in 60 which condensate is withdrawn from the condenser through the pipe g by the pump g , and aerated vapor is withdrawn from the heater c , together it may be with the heated water, through the pipe l by the pump u . Condensing water is supplied from the tank

r to the heater c under the control of a valve e , and may be discharged from the heater into the condenser through the pipes w and u , valves p and i being provided whereby the temperature of the water can be controlled 70 in the manner described with reference to Fig. 2. The discharge pipe from the pump g contains a non-return valve z which automatically closes and prevents the leakage of air into the vacuum system through the pipe 75 l should the supply of condensate cease.

Fig. 5 is a further modification of Fig. 2. In this example the aerated vapor is withdrawn from the heater c by a steam jet device 1 by which it is delivered into the water 80 jet air ejector 2 that is supplied under pressure with water from the tank 3 by the pump 4. Condensate is discharged from the condenser to the tank 3 by a two-stage pump g , the pipe f being connected to the 85 first stage pump so that a quantity of water may be delivered into the heater c through the valve e , the heated water being delivered from the heater through the pipe w into the condenser in the manner hereinbefore described 90 whereby the temperature of the water can be controlled.

In Fig. 6 the aerated vapor is withdrawn from the heater c , it may be together with the heated condensate, by a mechanically 95 operated air expelling device 5. The temperature of the condensing water discharged from the heater c may, when required, be controlled by the valves p and i by which the water may be cooled in the condenser in 100 the manner hereinbefore described.

Fig. 7 is a modification of Fig. 2, and in which the aerated vapor is withdrawn from the heater c by the mechanically operated rotary air expelling device 6, the temperature of the condensing water for use in the heater c being controlled by the valve i in 105 the manner hereinbefore described.

What I claim is:—

1. In steam condensing apparatus, the 110 combination with a main steam condenser of a steam jet device arranged to discharge aerated vapor from the condenser into a heater, a pump for discharging the condensate from said condenser, means for admitting condensate discharged from said pump into said heater, means for withdrawing the aerated vapor and heated water from said heater and means for cooling said heated water in the condenser when required, for 115 the purpose specified.

2. In steam condensing apparatus, the 120 combination with a main steam condenser of a steam jet device arranged to discharge aerated vapor from the condenser into a 125 direct contact heater, a pump for discharging the condensate from said condenser into a tank, a valve for supplying water from said tank into said heater, means for withdrawing the aerated vapor and heated water 130

from said heater and means for cooling said heated water in the condenser when required, for the purpose specified.

3. In steam condensing apparatus, the combination with a main steam condenser of a steam jet device arranged to discharge aerated vapor from the condenser into a direct contact heater, a pump for discharging the condensate from said condenser, means for admitting condensate discharged from said pump into said heater, means for withdrawing the aerated vapor from said heater, a water sealed looped pipe connecting the heater with the upper and lower portions of said condenser and means whereby the heated water can be delivered into the upper or lower portions of the condenser for the purpose specified.

4. In steam condensing apparatus, the combination with a main steam condenser of a steam jet device arranged to discharge aerated vapor from the condenser into a direct contact heater, a pump for discharging the condensate from said condenser into a tank, a valve for supplying water from said tank into said heater, a reciprocating air pump for withdrawing aerated vapor together with heated water from said heater and means for passing heated water withdrawn from said heater into the condenser when required, for the purpose specified.

5. In steam condensing apparatus, the combination with a main steam condenser of a steam jet device arranged to discharge aerated vapor from the condenser into a direct contact heater, a reciprocating air pump for discharging the condensate from said condenser into a tank, a valve for supplying water from said tank into said heater, another reciprocating air pump for withdrawing aerated vapor together with heated water from said heater, and means for passing heated water from said heater into the condenser when required, for the purpose specified.

6. In steam condensing apparatus, the combination with a main steam condenser of a steam jet device arranged to discharge aerated vapor from the condenser into a direct contact heater, a reciprocating air pump for discharging the condensate from said condenser into a tank, a valve for supplying water from said tank into said heater, another reciprocating air pump for withdrawing aerated vapor and heated water from said heater, a water sealed looped pipe connecting the heater with the upper and lower

portions of said condenser and valves whereby heated water may be delivered into the upper or lower portion of the condenser, for the purpose specified.

7. In steam condensing apparatus, the combination with a main steam condenser of a steam jet device arranged to discharge aerated vapor from the condenser into a direct contact heater, a pump for discharging the condensate from said condenser, a valve for admitting condensate discharged from said pump into said heater, a reciprocating air pump for withdrawing aerated vapor from said heater, means for cooling said air pump, a water sealed looped pipe connecting said heater with the upper and lower portions of said condenser and a valve whereby heated water can be delivered into the upper or lower portions of the condenser, for the purpose specified.

8. The combination with a steam condenser having separate outlets for aerated vapor and for condensate, of a steam jet device connected to the aerated vapor outlet, a heater into which said steam jet device discharges, a pump connected to said heater for withdrawing the aerated vapor and heated water therefrom, means for cooling the heated water in said condenser, a pump connected to the condensate outlet from said condenser, and means for connecting together the suction systems of both pumps for the purpose of withdrawing aerated vapor and condensate direct from the condenser when required.

9. The combination with a steam condenser having separate outlets for aerated vapor and for condensate, of a steam jet device connected to the aerated vapor outlet, a heater into which said steam jet device discharges, a pump connected to said heater for withdrawing the aerated vapor therefrom, a water sealed looped pipe connecting said heater with said condenser, a pump connected to the condensate outlet from said condenser, and means for connecting together the suction systems of both pumps for the purpose of withdrawing aerated vapor and condensate direct from the condenser when required.

Signed at West Hartlepool, in the county of Durham, England, this sixth day of April 1914.
